CLAIM

The ornamental design for a puzzle, as shown and described.

DESCRIPTION

FIG. 1 is an isometric view of a first embodiment of a puzzle showing my new design.

FIG. 2 is a front orthographic view thereof, the rear, left side, and right side orthographic views being identical thereto.

FIG. 3 is a top orthographic view thereof, the bottom orthographic view being identical thereto; and,

FIG. 4 is an isometric view of a second embodiment of a puzzle showing my design.

The broken lines shown in FIGS. 1-5 are included for the purpose of illustrating environmental elements only and form no part of the claimed design.
